(57) **CLAIM**

The ornamental design for a hydrogen gas cylinder assembly as shown and described.

DESCRIPTION

FIG. 1 is a top, front, left side perspective view of the hydrogen gas cylinder assembly embodying the design according to a first embodiment;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a longitudinal sectional view taken along lines 8-8 of the hydrogen gas cylinder assembly of FIG. 7, the hydrogen gas cylinder assembly enclosing a hydrogen gas cylinder;

FIG. 9 is a top, front, left side perspective view of the hydrogen gas cylinder assembly embodying the design according to a second embodiment;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof; and,

FIG. 16 is a longitudinal sectional view taken along lines 16-16 of the hydrogen gas cylinder assembly of FIG. 15, the hydrogen gas cylinder assembly enclosing a hydrogen gas cylinder.

The broken lines in the drawings illustrate portions of the hydrogen gas cylinder assembly that no form no part of the claimed design.
